US00D470440S

(12) **United States Design Patent** (10) Patent No.: **US D470,440 S**
 Rose et al. (45) Date of Patent: **** Feb. 18, 2003**

(54) **BICYCLE SHOCK ABSORBER LOWER TUBE ASSEMBLY**

(75) Inventors: **Russell J. Rose**, Colorado Springs, CO (US); **Mark Norris**, Colorado Springs, CO (US)

(73) Assignee: **RockShox, Inc.**, Colorado Springs, CO (US)

(**) Term: **14 Years**

(21) Appl. No.: **29/134,634**

(22) Filed: **Dec. 26, 2000**

(51) LOC (7) Cl. **12-11**

(52) U.S. Cl. **D12/118**

(58) Field of Search **D12/111, 117, D12/118; 280/276-280, 281.1, 288.1-288.3**
